DESIGN FOR A TEXTILE FABRIC

Robert S. Gentile, New York, N. Y., assignor to Tabin-Picker & Company, Chicago, Ill., a corporation of Illinois

Application April 22, 1940, Serial No. 91,839

Term of patent 3½ years

To all whom it may concern:

Be it known that I, Robert S. Gentile, a citizen of the United States, residing in New York city, in the county of New York and State of New York, have invented a new, original, and ornamental Design for a Textile Fabric, of which the following is a specification, reference being had to the accompanying drawing, forming a part thereof.

The figure is a plan view of a textile fabric showing my design.

The design consists of a series or plurality of equidistantly spaced parallel stripes of relatively narrow width of contrasting color separated by contrasting lines or narrower stripes and each series of stripes separated by stripes of one contrasting color wider than the width of each series of stripes.

I claim:

The ornamental design for a textile fabric, as shown and described.

ROBERT S. GENTILE.
